UNITED STATES PATENT OFFICE.

LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

HORIZONTAL FLUE.

Application filed September 25, 1923. Serial No. 664,694.

To all whom it may concern:

Be it known that I, LOUIS WILPUTTE, a citizen of the United States, and resident of New Rochelle, in the county of Westchester and State of New York, have invented certain new and useful Improvements in Horizontal Flues, of which the following is a specification.

My present invention relates to coke ovens of the kind in which each heating wall at the side of a coking chamber is formed with vertical combustion flues connected with one or more chambers or flues above the vertical flues therein and each serving to connect two or more of the vertical flues beneath it. With this type of heating wall, which is that employed in a great majority of the by-product coke ovens now in use, it is desirable to restrict the upper end of each vertical flue to provide a port connecting the body portion of the flue with the connecting chamber or horizontal flue above it, which is substantially smaller in cross section than the body portion of the vertical flue. This restriction is necessary in practice to control combustion in the vertical flues, and to regulate the proper distribution of flow of the heating gases among the different vertical flues in the heating wall.

Heretofore it has been the universal practice in constructing coke oven heating walls of the kind mentioned to secure the restricted connection between the vertical flues and the connecting chamber or horizontal flue above them by what amounts to a thickening of the wall portions between the flues and the adjacent oven chambers, and between the adjacent vertical flues. This thickening of the walls at the sides of the oven chambers reduces the rate of heat transfer to the coking charge in the oven chambers at the level of the restricted ports connecting the vertical flues to the connecting chambers or horizontal flues above them, so that it is practically impossible to avoid underheating of the charge at this level without either overheating the main portions of the charge, or subjecting the charge to a heat equalizing or "soaking" operation which undesirably prolongs the coking period.

The difficulty of properly heating the top

portions of the charges is augmented, moreover, by the fact that to avoid overheating the distillation gases in the gas collecting spaces above the charges in the oven chambers, the upper horizontal channels or chambers to which the tops of the vertical flues are connected are ordinarily located below the tops of the charges in the oven chambers.

A main object of the present invention is to provide a simple and effective heating wall construction which will permit any desirable restriction in area of the ports connecting the upper ends of the vertical flues to the connecting chamber of flues without causing a reduced rate of heat transfer into the charge at the level of these ports, and will also permit inspection of the vertical flues, and of the gas burner nozzles ordinarily provided at the bottom of those flues, and the cleaning or renewal of those nozzles in the usual manner when necessary. In the preferred arrangement devised by me for attaining this object, I form the upper portion of the partition walls between adjacent vertical flues by bricks provided with extensions which project across the vertical flues, and are shaped to provide ports between the vertical flues and the connecting chambers or flues above them, some of which are adjacent the sides of the heating walls, while one is a central port large enough in diameter to permit the passage of the corresponding gas nozzle. Each of these central ports is normally obstructed by a plug which may be removed to permit the nozzle to be cleaned or replaced. This plug is preferably provided with a relatively small orifice through which the nozzle may be inspected in operation without removal of the plug.

A second main object of my invention is to provide for an increased velocity of the heating gases in the vertical flues, and particularly in the upper portions of those flues to thereby increase the rate at which heat is imparted to the upper portions of the charges being coked. This object I readily attain in accordance with the present invention, by means of brick work partitions in the vertical flues which serve in effect to extend the above mentioned ports provided to attain the first mentioned ob-

ject of the invention, downward through the portion of the flue in which the high gas velocity is desired.

A third main object of the invention is to provide for the transfer of an adequate amount of heat to the portions of the oven charges above the level of the flow restricting ports while at the same time minimizing the danger of overheating the distillation gases in the gas collecting spaces formed by the top portions of the oven chambers. This I accomplish by making the side walls of the horizontal flues or chambers to which the tops of the vertical flues are connected of increasing thickness from bottom to top. This feature of construction is especially advantageous when employed in conjunction with means for attaining the above mentioned objects of my invention owing to the manner in which the heating gases pass upward from the tops of the vertical flues.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter, in which I have illustrated and described preferred embodiments of my invention.

Of the drawings:

Fig. 1 is a diagrammatic elevation of one common form of vertically flued heating wall in which my invention is advantageously employed;

Fig. 2 is a partial vertical section through the heating wall;

Fig. 3 is a partial vertical section on the line 3—3 of Fig. 2;

Fig. 4 is a partial section on the line 4—4 of Fig. 2;

Figs. 5 and 6 are perspective views, each showing a different brick employed in the construction shown in Figs. 2 and 3;

Figs. 7 and 8 are views taken similarly to Fig. 4 and each illustrating a different modification of the restricted port arrangement shown in Fig. 4;

Figs. 9 and 10 are diagrammatic views illustrating a different form of heating wall flue system with which the present invention may advantageously be employed;

Fig. 11 is a partial section taken similarly to Fig. 2, illustrating a modified construction; and

Fig. 12 is a partial section on the line 12—12 of Fig. 11.

In Figs. 2 to 6 inclusive, I have illustrated a preferred construction especially devised and adapted for use in a heating wall having the flue system diagrammatically illustrated in Fig. 1. This flue system, which

has been in use for more than a generation and is that employed in the majority of by-product coke ovens in operation in this country at the present time, is one in which a series of vertical heating flues B in each heating wall are connected at their upper ends by a common horizontal flue C, and in which the heating gases, at any one instant, flow upward through all the flues B in the heating wall at one side of a central flow reversal plane X—X, into the upper horizontal flue C, and pass from that flue into the upper ends of the vertical flues B at the opposite sides of said flow reversal plane. The flues B at the opposite sides of the flow reversal plane are connected to separate regenerators, and the direction of gas flow through the vertical flues B, and through the upper horizontal channels C, is reversed at regular intervals of a half hour or so.

In the heating wall construction illustrated in detail in Figs. 2 to 6 inclusive, the walls of the body portions of the vertical flues are ordinarily formed by the so-called bottle brick D which separates the adjacent vertical flues, and by the side wall bricks E which are interposed between the flues B and the adjacent coking chambers A. A regenerator port F, and a gas well G are formed at the bottom of each vertical flue B. Seated at the bottom of each gas well G, is a fire clay nozzle H having a measuring orifice proportioned to deliver the proper amount of combustible gas to the flue B from the gas supply channel I formed in the oven brick-work below the corresponding flues B. The side walls of the horizontal flues C are formed by bricks J, and inspection channels B' are formed in the brickwork forming the roof of the oven structure, one in alignment with each vertical flue B. Each channel B' is normally closed at its upper end by a removable cap B². When any cap B² is removed, combustion conditions in the portion of the heating wall flue system beneath the corresponding channel B' may be observed, carbon deposits may be punched out of the corresponding nozzle H by a rod inserted through the open channel B', and, if necessary, the nozzle H may be replaced by a new nozzle inserted through this channel. In so far as above described, the construction shown in Figs. 2 and 6 is of a type which is now, and long has been in extensive use.

The constructions shown in Figs. 2 to 6 differ, however, from those heretofore in use, in the manner in which the restricted ports between upper ends of the vertical flues B and the horizontal channel C are formed. The means for this purpose illustrated in Figs. 2 to 6, comprise a specially shaped bottle brick K at the top of the partition wall between each adjacent pair of vertical flues, or preferably, as shown immediately beneath an ordinary bottle brick D

at the very top of that wall. The bottle brick K differs from the ordinary bottle brick, in having lateral projections or wings K' at each side, which extend approximately half way across the corresponding vertical flue B, and serves in conjunction with the wing K' of the corresponding bottle brick at the opposite side of the flue to form an apertured diaphragm or bridge across the upper end of the flue B. This bridge does not entirely close the upper end of the flue B, however, but on the contrary, the wings K' are shaped and proportioned to provide a slot-like port L adjacent each side of the heating wall. Each port L as shown in Figs. 2 to 6, is separated from the adjacent oven chamber by a side wall brick E of the same thickness as the side wall bricks employed at immediately subjacent levels. Each wing K' is also formed with a central notch in its free edge which cooperates with the corresponding notch in the adjacent wing K' to form a port K² in alignment with the corresponding inspection channel B', and somewhat larger than is required to permit the passage of a gas nozzle H.

Advantageously the bottle brick wings K' are formed with recesses K³ in their upper sides, the recesses K³ in each adjacent pair of wings cooperating to provide a seat for a rectangular brick or block M which is formed with a port M' which is in axial alignment with the corresponding port K² and inspection channel B', and is of sufficient diameter to permit the passage of a gas nozzle H. In the preferred construction illustrated, the port M' is enlarged at its upper end to provide a seat for a disc or plug O which is provided with a central orifice O', smaller in diameter than the gas nozzle H, but large enough to permit visual inspection of a nozzle H at the bottom of the corresponding flue through the corresponding inspection channel B'. Advantageously the bottle brick DA immediately beneath each special bottle brick K, differs from the ordinary bottle bricks, in having lateral lugs D' which serve as supporting abutments for the wing portions K' of the brick K above it. Advantageously the lugs K', the end edges of the wings K', and the lower portions of the notches K² are tapered as shown.

With the described construction, the gas flow between each vertical flue B and the channel C will be partly through the ports L, and partly through the plug orifice O'. Ordinarily I contemplate such relative port proportions that the bulk of the gas flow will be through the ports L, but an appreciable flow through each port O' may be desirable to prevent overheating of the oven walls at the level of the ports L, where the high velocity of the heating gases tends to an especially high heat transfer coefficient.

The fact that each plug O may readily be removed through the corresponding channel B', and may be replaced by another plug O, having an orifice O' of different diameter, makes it possible to adjust the aggregate port area connecting each vertical flue B to the channel C, if this becomes desirable. The character of the restriction desirably provided in the port connection between each vertical flue and the upper horizontal channel, and the desirability of providing devices, such as are formed by the removable apertured plugs O, for regulating the aggregate port area, will be recognized by those skilled in the art, and are indicated by the fact that in the well known and successful type of coke oven known as the Wilputte oven, the horizontal cross section of each vertical flue is in the neighborhood of 140 to 160 square inches, while the area of the port connecting each vertical flue to the upper horizontal flue varies from something like 2½ square inches in cross-section for a vertical flue adjacent the flow reversal plane X—X, to something like 20 or 25 square inches for a flue adjacent the end of the heating wall.

The combustion conditions in each vertical flue B may be readily observed, and the gas nozzle H at the bottom of the flue may be readily inspected through the orifice O' in the corresponding plug O without removal of the latter. When it is necessary to clean or replace a gas nozzle H, the corresponding plug O may be moved from its seat into an adjacent portion of the upper horizontal channel C, or may be withdrawn from the oven structure through the corresponding inspection channel B'. With the plug O thus out of the road, the gas nozzle H may be cleaned, or replaced in the usual manner now followed in effecting such nozzle cleaning and replacement operations.

In some cases it may be possible to dispense with the bricks M, and to seat suitable shaped plugs O directly in the ports K². In ordinary practice, I prefer, however, to employ the bricks M, as these bricks, which may well be cemented or mortared in place, provide more uniform seats for the plugs O than would ordinarily be provided by the abutting sections K'. It will be obvious that instead of making the ports adjacent the sides of the heating walls in the form of narrow slots L as shown in Figs. 2 and 4, these ports may be otherwise formed and disposed. For example, they may be formed by notches K⁴ in the ends of the wing ports K' as shown in Fig. 7, or by a series of holes K⁵ in the wing sections adjacent but slightly displaced from the side wall bricks E, as in the construction shown in Fig. 8.

While the features of my invention already described may be used with advan-

tage in ovens having the side walls of the upper horizontal channels C formed in the usual manner, I advantageously employ the special horizontal flue wall construction 5 shown in which the bricks J are not rectangular, but trapezoidal in cross section so that the sidewalls of the channels C increase in thickness from top to bottom. As shown in Fig. 2 both the inner and outer sides of 10 said side walls are inclined from the vertical and in Fig. 11 only the inner side is inclined. With this wall arrangement, overheating of the distillation gases in the spaces above the oven charges X may be avoided, 15 while at the same time the top portions of the charges X are properly heated and the upper portion of the heating wall is made strong and stable. The fact that the heating gases pass from the vertical flues into 20 the upper horizontal flues C, upward along the side walls of the latter, makes it possible to obtain full advantage of the varying thickness of said walls as a means for regulating the heat imparted to the upper 25 portion of the oven chambers. With the described construction, the upper horizontal flues C may be desirably large in cross section, which, in conjunction with the smooth inner surfaces of their side walls, insured 30 a relatively low resistance to longitudinal gas flow through the channels.

The various features of my invention may be used with advantage in heating walls in which the flue systems are quite different 35 from that shown in Fig. 1, such as those shown in Figs. 9 and 10. In the flue system shown diagrammatically in Fig. 9, there are a plurality of groups of vertical heating flues in each heating wall, with the flues B 40 in each group connected by a corresponding flue or channel CA which is in communication with a corresponding channel in the heating wall at the opposite side of an adjacent oven through a port C¹⁰. In the flue system diagrammatically illustrated in Fig. 45 10, each adjacent pair of vertical flues B in a single heating wall are connected by a corresponding flue space or connecting chamber CB above the flues. In the flue systems 50 shown in Figs. 9 and 10 the same general necessity for restricting the port area between each vertical flue and the connecting chamber or flue space above it, exists as in the flue system shown in Fig. 1, and in general 55 with the flue system shown in Figs. 8 and 10, the same necessity or desirability for inspection and for cleaning and replacing nozzles exists as in the flue system shown in Fig. 1.

60 In the special construction illustrated in Figs. 11 and 12, two partitions are formed in the upper portions of each vertical flue, extending downward from the bricks K and serving in effect to prolong the ports L and 65 K². Each partition is formed advan-

geously of bricks Q placed on edge one above the other, and each having its end edges received in notches in the corresponding specially shaped bottle brick DB at the opposite sides of the flue. The lower brick Q 70 in each partition rests on lugs D¹⁰ formed for the purpose on the sides of the subjacent bottle brick DC, and the bottle brick DA immediately beneath the bottle brick DC are provided with tapered lugs D' on 75 the inverted bases of which the lugs D¹⁰ bear. The top most bricks Q in the partitions serve in lieu of the lugs D' of the bricks DA employed in the construction first described, to support the wings K' of the 80 bricks K.

With the construction illustrated in Figs. 11 and 12, the velocity of heating gas flow through the upper portions of the heating flues obviously depends upon the distance 85 between each partition formed by the bricks Q, and the adjacent side wall bricks E, and may be increased and diminished by decreasing and increasing said distance. An increased heating gas velocity in the upper 90 portions of the vertical flues desirably increases the heat transfer rate from those portions of the flues to the coking charges and tends to shorten the time required for a coking operation. The increased gas velocity is obtained, moreover, without reducing the thickness and mechanical strength of the heating walls and without thickening the walls between the vertical flues and the oven 95 chambers. The bricks Q carry no real load, 100 and are preferably loosely set in place and not mortared, and in consequence will safely withstand very high temperatures. The relative lengths of the portions of each vertical flue above and below the lower edges 105 of the partitions formed by the bricks Q may be varied as desired. With the arrangement shown in Figs. 11 and 12, the apertures O' in the removable discs O are made as small 110 as possible, and may be omitted.

While in accordance with the provisions of the statutes, I have illustrated and described the best forms of my invention now known to me, it will be apparent to those skilled in the art that some changes in form may be made without departing from the spirit of my invention as set forth in the appended claims, and that some features of my invention may sometimes be used to advantage without a corresponding use of other 115 features.

Having now described my invention, what I claim as new and desire to secure by Letters Patent, is:

1. In a coke oven heating wall formed 125 with vertical flues and a flue space or spaces connecting adjacent ones of said flues at their upper ends, the improvement which consists in a brickwork portion of said wall shaped to provide a port between each vertical flue 130

and the space to which its upper end is connected which is substantially smaller in cross section than the flues itself and comprises portions adjacent the sides of the heating wall.

5. 2. In a coke oven heating wall formed with vertical flues and a flue space or spaces connecting adjacent ones of said flues at their upper ends, the improvement which 10 consists in a brickwork portion of said wall shaped to provide a port between each vertical flue and the space to which its upper end is connected adjacent each side of the heating wall, and a central nozzle passage, 15 and a removable plug for said passage.

3. In a coke oven heating wall formed with vertical flues and a flue space or spaces connecting adjacent ones of said flues at their upper ends, the improvement which 20 consists in a brickwork portion of said wall shaped to provide a port between each vertical flue and the space to which its upper end is connected adjacent each side of the heating wall, and a central nozzle passage, 25 and a removable apertured plug for said passage.

4. In a coke oven of the type comprising heating walls each formed with a plurality of vertical heating flues with a removable 30 gas nozzle at the bottom of each flue and with a flue space or spaces above the vertical flues to which the latter are connected and with inspection openings in the roof of the oven structure opening at their lower ends 35 into said flue space or spaces, the improvement which consists in brickwork extending across the top of each vertical flue and formed with a central nozzle passage and with one or more ports between said passage 40 and each side of the heating wall, and a plug removably mounted in said passage-way and formed with an orifice substantially smaller in diameter than said passage-way.

5. In a coke oven heating wall comprising vertical flues with brick division walls between adjacent flues, the improvement which consists in a brick adjacent the top of each division wall provided with wing 50 portions at each side, each extending substantially half way across the corresponding flue and being formed with a notch in its side edge which cooperates with a notch in the adjacent wing edge of the corresponding 55 brick at the opposite side of the flue to form a port located centrally of the flue, said wing portions being shaped and proportioned to provide ports between their end edges and the adjacent flue walls.

6. In a coke oven heating wall formed with vertical flues, means for obtaining a relatively high heating gas velocity in the upper portions of said flues comprising two 60 vertical partitions in each flue, parallel to

the sides of said walls and spaced away 65 from the inner walls of the flue and from each other whereby the flue space is divided into two open ended channels, one adjacent each side of the flue space and an intermediate passage, and means restricting flow 70 through said passage.

7. In a coke oven heating wall formed with vertical flues, means for obtaining a relatively high heating gas velocity in the upper portions of said flues comprising two 75 vertical partitions in each flue, extending parallel to the sides of said walls and spaced away from the inner walls of the flues and from each other, whereby the flue space is divided into two open ended channels, one adjacent each side of the flue space, and an intermediate passage, and removable means 80 restricting flow through said passage.

8. In a coke oven heating wall formed with vertical heating flues and intervening 85 division walls formed with grooves in their sides, flue partition walls formed by bricks each of which extends across a flue space and has its ends received in the corresponding division wall grooves. 90

9. In a coke oven comprising oven chambers and heating walls at the sides of said chambers and formed with horizontal heating flues adjacent the tops of the oven chambers, the improvement which consists in a 95 heat transmitting wall between each such flue and the adjacent oven chamber of tapering thickness with its thickest portion at the top.

10. In a coke oven comprising oven chambers and heating walls at the sides of said chambers and formed with horizontal heating flues adjacent the tops of said chambers, the improvement which consists in a heat 100 transmitting wall located between each such flue and the adjacent oven chambers and having its inner surface inwardly inclined to increase the thickness of the upper portion of said wall and means for passing 105 heating gases into and out of said flues 110 along the side walls of the latter.

11. In a coke oven comprising coking chambers and heating walls between the chambers and formed with vertical flues and upper horizontal channels each of which extends over a plurality of vertical flues, the improvement which consists in side walls for said horizontal channels which have their inner surfaces inwardly inclined to give increased thickness to the top portions of said walls, and a bottom wall for each said horizontal channel formed with ports adjacent said walls connecting the channel to the subjacent vertical flues. 115 120

Signed at New York city in the county of New York and State of New York this 21st day of September, A. D. 1923.

LOUIS WILPUTTE.
